(57) **CLAIM**

The ornamental design for a patient table for medical imaging system, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a front elevational view of a first embodiment of a patient table for medical imaging system;

FIG. 2 is a rear elevational view of the patient table for medical imaging system of FIG. 1;

FIG. 3 is a top plan view of the patient table for medical imaging system of FIG. 1;

FIG. 4 is a bottom plan view of the patient table for medical imaging system of FIG. 1;

FIG. 5 is a right side elevational view of the patient table for medical imaging system of FIG. 1;

FIG. 6 is a left side elevational view of the patient table for medical imaging system of FIG. 1;

FIG. 7 is a perspective view from a direction between the front and right side of the patient table for medical imaging system of FIG. 1;

FIG. 8 is a perspective view from a direction between the rear and right side of the patient table for medical imaging system of FIG. 1;

FIG. 9 is a front elevational view of a second embodiment of a patient table for medical imaging system;

FIG. 10 is a rear elevational view of the patient table for medical imaging system of FIG. 9;

FIG. 11 is a top plan view of the patient table for medical imaging system of FIG. 9;

FIG. 12 is a bottom plan view of the patient table for medical imaging system of FIG. 9;

FIG. 13 is a right side elevational view of the patient table for medical imaging system of FIG. 9;

FIG. 14 is a left side elevational view of the patient table for medical imaging system of FIG. 9;

FIG. 15 is a perspective view from a direction between the front and right side of the patient table for medical imaging system of FIG. 9; and,

FIG. 16 is a perspective view from a direction between the rear and right side of the patient table for medical imaging system of FIG. 9.

Portions of the patient table for medical imaging system shown in broken lines form no part of the claimed design.
